UNITED STATES PATENT OFFICE.

JOHN UNSER, OF CARTHAGE, NEW YORK.

COLLAPSIBLE LUNCH BOX.

Application filed February 12, 1923. Serial No. 618,547.

To all whom it may concern:

Be it known that I, JOHN UNSER, a citizen of the United States, residing at Carthage, in the county of Jefferson and State of New York, have invented certain new and useful Improvements in Collapsible Lunch Boxes; and I do declare the following to be a full, clear, and exact description of the invention such as will enable others skilled in the art 10 to which it appertains to make and use the same.

This invention relates broadly to an improved lunch box, and it has more particular reference to the type of boxes which are 15 such as to permit them to be collapsed to render them compact for convenient transportation when not in use.

It is the principal object of the invention to generally improve upon collapsible lunch 20 boxes by providing one of extreme simplicity and durability which is of such construction that the sides and ends can be automatically and simultaneously brought in position to form a complete box by simply 25 pulling on the cords which are slidably connected with the foldable flaps forming the ends of the box.

More specifically speaking, it is another 30 object of the invention to provide a box of the foregoing construction wherein the free ends of the pull cords are adapted to be extended across the top of the box in opposite directions, said free ends being adapted to be detachably connected with unique anchoring means on the ends of the box so that 35 the cords are then permitted to serve the additional function of a handle for conveniently carrying the box.

Other objects and advantages of the invention 40 will be apparent during the course of the following description.

In the accompanying drawings forming a part of this specification and in which like numerals are employed to designate like 45 parts throughout the same:—

Figure 1 is a perspective view of the blank from which the box is formed, the end flaps being folded inwardly upon their respective sides.

Fig. 2 is also a perspective view showing 50 the cords partially pulled, with the sides and flaps about to assume their operative positions.

Fig. 3 is a perspective view of the complete box showing the manner in which the handle is formed.

Fig. 4 is a longitudinal section of one end of the box.

Fig. 5 is a detail perspective view of one end of the box showing a slightly modified 60 anchoring means for the pull cords.

Fig. 6 is likewise a similar view showing the cord associated therewith.

As before intimated, the improved box is 65 formed from a paper-board blank which is cut to provide a bottom 1, vertical sides 2, a top 3 and a plurality of foldable flaps 4 and 5 connected with the sides and bottom respectively. As is usual, in order to permit accurate folding of these portions to 70 form the box, they are connected together by scores in the usual way. In order to permit the parts to be automatically and simultaneously folded to operative position, the several flaps are provided with openings 75 surrounded by reinforced eyelets 6 and a pair of pull cords are passed through these eyelets. Hence, when the free ends of the cords are grasped and pulled, the sides 2 will be raised into vertical spaced parallelism and the end flaps will be disposed in 80 overlapping relation. For the purpose of permanently connecting the cords 7 with the flaps, knots are tied on the opposite ends of the cords and washers 8 and 9 are associated with these. The first named washers 85 bear against the inner faces of the flaps 5.

As hereinbefore pointed out, it is one of the main features of this invention to extend the free ends of the pull cords over the 90 top of the box so that they may serve the additional function of a handle for carrying the latter and to permit this result to be accomplished, I associate unique anchoring means with the ends of the box. At this point, I wish to state that the anchoring means could of course vary in construction and for the purpose of illustration I have shown two methods which I contemplate using. Attention being first confined to the 100 anchoring means employed in Figs. 1 to 4 inclusive, it will be seen that this simply comprises a pair of disk-like paper members 10 secured to the outermost flaps 4. By carefully examining the anchoring disks it 105 will be noted that each one is formed in its periphery with a notch 11 which serves a purpose to be hereinafter described.

Assuming that it is desired to unfold the blank for the purpose of forming the box, the washers 10 on the free ends of the cords are grasped and the two cords are pulled 110

through the eyelets 6. As soon as the pull is exerted on the cords, it will be seen that the parts will assume the approximate relative positions shown in Fig. 2. Exerting 5 a still further pull on the cords, the flaps 4 and 5 will be disposed in overlapping relation and the sides 2 will be disposed in spaced vertical relation and the box will be complete for use. Of course, in order 10 to close it, the top 3 can then be swung down. Now, in order to maintain the foldable portions in their upright operative positions, the cords are drawn tightly and the inner end portions thereof are passed 15 through and drawn into the seats of the notches 11 in the anchoring disks 10 and then between the disks and flaps 4 to hold the cords against slipping. After this, the free end of each pull cord is passed over the 20 top of the box in the direction opposite to that of the other cord and the free ends are engaged with the then adjacent anchoring disks with the washer associated with the aforesaid notches in the manner illustrated 25 more clearly in Fig. 3. By reversing the procedure just outlined, the box may be again collapsed for shipment or transportation. The foregoing paragraph covers that form of the invention shown in Figs. 30 1 to 4, inclusive.

As already disclosed, it is not desired to restrict the invention to any particular anchoring means for the free ends of the cord. I now direct attention to Figs. 5 and 6, 35 wherein I have shown another form of anchoring means for the free ends of the pull cords. Reference being had to these figures, it will be seen that the box itself is identical with that hereinbefore described. Therefore, the same reference characters will apply 40 to these figures so far as the box is concerned. The anchoring means which I employ however, is varied in construction and in carrying out this end, I cut the outermost 45 flap 4 to provide a disk-like anchoring head 12, this head being integral with the flap. By so designing the head, a pair of notches 13 and 14 are provided at its point of connection with the flap. By directing attention 50 now to Fig. 6 it will be seen that in use the inner end portion of one pull cord at the end of the box shown is, after being drawn tightly through the alined holes in the flaps, seated in the notch 13, drawn 55 across the rear side of the head 12 and passed upwardly through the notch 14 and then across the top of the box. The free end of the cord from the other end of the

box is likewise passed through the notch 13, and behind the flap so as to permit the free end with the washer to be seated in the other notch 14. Hence, the flaps of the box are maintained in operative condition and the portions of the cords which pass over the top of the box provide a handle 60 for conveniently carrying the latter from place to place.

By carefully considering the description in connection with the drawings, persons familiar with devices of this class will 65 doubtless be able to obtain a clear understanding of the invention. Therefore, a more lengthy and detailed description is deemed unnecessary.

Since probably the best results may be 70 obtained with the construction and arrangement herein shown and described, this is taken as the preferred embodiment of the invention. However, I wish it to be understood that minor changes coming within 75 the scope of the invention as claimed may be resorted to if desired.

I claim:

1. A folding lunch box comprising a plurality of sides connected by scores, said sides 85 being provided with foldable flaps arranged in overlapping relation, said flaps having alined holes, separate cords passing slidably through the holes, washers on the ends of the cords, the washers on the inner ends 90 of the latter being adapted to bear against the inner faces of the end flaps on the bottom of the box, the free ends of the cords being adapted to pass in opposite directions over the top of the box, and anchoring means 95 secured on the ends of the box with which the washers on the free ends of the cords are detachably connected.

2. A folding lunch box comprising a plurality of sides connected together by cords, 100 said sides being provided with foldable end-flaps arranged in overlapping relation, said end-flaps being provided with alined holes, separate cords passing slidably through said 105 holes and connected at their inner ends with said flaps, the free outer ends of said cords being adapted to pass in opposite directions over the top of the box to provide a handle for carrying the latter, and anchoring means secured to said flaps, the free ends of said 110 cords being adapted to be detachably connected with said anchoring means.

In testimony whereof I have hereunto affixed my signature.

JOHN UNSER.
